UNITED STATES PATENT OFFICE.

HARRY BRIDGMAN SMITH, OF NEW YORK, N. Y.

COVERED BOX.

Application filed April 23, 1921. Serial No. 463,755.

To all whom it may concern:

Be it known that I, HARRY BRIDGMAN SMITH, a citizen of the United States, and resident of New York city, in the county of Kings and State of New York, have invented certain new and useful Improvements in Covered Boxes, of which the following is a specification.

My invention relates to covered paper boxes.

The principal object of the invention is to provide a covered box which closely resembles covered boxes of the most expensive kinds, but which differs from these expensive boxes in certain structural features, so that the cost of manufacture is materially reduced. By these structural changes I am enabled to produce a box which is satisfactory for many uses, and which differs so 20 slightly from the more expensive covered boxes that the differences are usually not noticeable except upon close inspection.

Covered boxes until recently have usually been made by first providing a shell of cardboard or similar material and then affixing a sheet of cover material of suitable quality and finish to the shell so as to completely cover the latter, marginal portions of the cover being turned in and secured to inner 30 marginal surfaces of the shell, so that a continuous marginal strip of the cover material appears around all sides of the interior of the box part. The cover material is arranged so that all edges of the shell material 35 are covered and from the outside the only surfaces visible are composed of the cover sheet. More recently, by structures and methods of my invention, covered boxes have been produced by first forming an assembly 40 consisting of a sheet of shell material and a sheet of cover material with marginal portions of the cover turned over and secured to opposite marginal portions of the shell, and this assembly is then folded up and secured 45 in complete box form in various ways, so that all portions of the shell, including edge portions, are entirely covered and concealed from view from the outside of the box part and a continuous marginal strip of the cover 50 material appears about the inside of the box, as in the case of previous structures and methods. The statements above made as to appearance of the boxes apply both to "tight" and "loose-wrapped" boxes, whether 55 made by old methods or methods of my invention.

While completely covered boxes of the class described are very desirable to meet the most exacting trade requirements, they are unduly expensive for certain purposes; and by study and experimentation, I have found that a desirable box having a satisfactory appearance, although the finish is not quite so perfect as in the case of the completely covered boxes above described, can be produced by modifying and simplifying the structure and production methods, resulting in a very substantial reduction in the cost of the boxes.

In one embodiment of the invention as disclosed herein, blank assemblies are first produced according to the general methods of my invention above briefly described, but suitably modified for the present purpose; that is to say, a blank of shell material is provided 70 which may be substantially rectangular in form without any irregularities and therefore without any waste of shell material; this is covered on one side with cover material of suitable quality, and two of the opposite margins of the cover material are folded over and adhesively secured to the opposite side of the shell. The blank is suitably creased for folding, and usually incisions are made to separate the end wings of 75 the blank from the corner laps. The blank is then folded up into box form with the corner laps inwardly turned within the end wings and adhesively secured thereto, the blank being usually designed so that the 80 now adjacent edges of the corner laps fit closely together. The result is a box in which the inturned marginal portions of the cover extend entirely around the inner surfaces of the box part at the open side and are 85 continuous except for breaks at the intersections of the corner laps. The interior appearance presented is, in other words, substantially that of a covered box of the most expensive type, and because of familiarity 90 with such covered boxes the mental impression given to the observer is that the box is one of the expensive class in question. The exterior of the box part is completely 95 covered, except for the free edges of the shell end wings which are exposed to view more or less when viewed edge-on, although they are not especially noticeable from any other point of view. The prominence of these exposed portions is still further reduced in the 100 preferred form of the invention by pressing down the cover material adjacent to these 105 110

edges, so that the parts fit very tightly at these points and the cover material in some cases is even extended somewhat over the edges of the shell material so that the latter 5 are still further obscured.

The characteristics and advantages of the invention are further sufficiently described in connection with a detail description of the accompanying drawing, which shows one 10 exemplifying embodiment of the invention.

After considering this, it will be understood that many modifications may be made within the principles of the invention, and I contemplate any structures which are properly 15 within the scope of the appended claims.

In the drawings:

Fig. 1 is a plan view of a blank assembly embodying the invention.

Fig. 2 is an end perspective of a box produced from the blank of Fig. 1.

Fig. 3 is a section of one end of the box in the plane of 3—3, Fig. 2.

Fig. 4 is a diagonal perspective of the same box.

According to my general method of box-blank assembly involving overturned cover margins, the assemblies may be produced either from separate blanks or from continuous sheets of material. Fig. 1 shows a flat 25 assembly comprising a sheet of shell material S and a sheet of cover material W having its margins h turned over and secured to the upper surface (which is to be the inner surface of the completed box) of 30 the shell material. The pieces of shell and cover material may be produced originally as separate blanks, or they may be advanced from continuous webs or rolls of material and cut off at suitable intervals to produce 35 the assemblies shown in Fig. 1. By whatever general method the blank assembly is produced, it comprises, in one representative embodiment, a body portion a, side wings b, end wings c and corner laps d extending 40 from the ends of the side wings, the corner laps being severed from the end wings by cuts along the lines e. The blank is desirably creased or scored to facilitate subsequent bending along the lines f and g. Desirably in the present instance the bending lines f are represented by relatively deep 45 creasing, and the lines g may be simple score lines. The entire shell blank S as viewed in 50 Fig. 1 is underlaid by the cover material 55 W, and usually the contacting faces of the shell and cover are adhesively secured over a large part of their areas or throughout their entire areas. At least the shell and cover material are desirably secured adhesively 60 throughout the marginal outlines of the end portions of the blank including the end wings and corner laps. The overturned marginal portions h of the cover are extended along the outer margins of the shell cor-

ner laps d, these portions of the cover margins being identified as h'.

The blank as shown is of simple rectangular outline, and obviously no material either of the shell or cover is wasted by reason of cut-out portions. The selected 70

dimensions of the blank are such that when it is folded up as shown in Figs. 2 and 4, the outer ends of the corner laps as they appear in Fig. 1 will fit closely together.

Since it is usually desired that these ends 75 or edges of the corner laps shall substantially meet, in the completed box, as later explained, it is evident that when the blank is of simple rectangular form its dimensions are limited; that is the bottom width

of the box part is substantially twice the length of the corner laps in the direction of the longitudinal axis of the box; and with these selected dimensions the corner laps 80

and end wings in the longitudinal direction 85 of the blank are of the same length, producing the straight or square-cut form of the blank as shown in Fig. 1. When it is

desired to vary the proportions of the box part the length of the corner laps and end 90 wings may be varied suitably; that is, when the width of the box bottom is less than twice the depth of the box, determined by the width of the side wings in the trans-

verse dimension of the box or the length of the end wings in the longitudinal direction, the corner laps must be cut off shorter than 95 the end wings so that their combined length is equal to the width of the box bottom; and if the width of the box is greater than twice the depth the corner laps must be cut longer than the end wings. In any case 100 the corner laps are proportioned so that their inner edges when folded up will closely meet or abut. It will be under-

stood, therefore, that the box here selected 105 to illustrate the invention is one example of the proper dimensioning of parts of the blank in accordance with the principle de-

scribed; that is it represents a case where 110 the width of the box bottom is twice the depth of the sides, and in that case the end wings and corner laps will be of substantially 115 the same length and the square-cut blank may be employed without waste of material as previously explained.

The blank is folded up with the end wings outside the corner laps at each end of 120 the box, and the outer surfaces of the corner laps are adhesively secured to inner sur-

faces of the end wings. This simple folding and gluing operation completes the box 125 in one desirable form of the invention. The inward edges of the corner laps fit closer together, and correspondingly the ends of the cover marginal portions h' fit very closely together and the inturned cover margins including the parts h' and h there-

fore form an apparently continuous strip about the inner marginal surface of the shell, substantially as in the case of the most expensive covered boxes as previously explained. The purchaser or user of the box, therefore, receives the impression that he is observing a covered box of the ordinary highly finished type, and while more or less uncovered margins of the shell end wings appear, for instance at *k* and *l*, Fig. 4, these will not easily be noticed except by close inspection. Furthermore, from such points of view as that of Fig. 2, the edges of the cover material over the shell end wings extend at least as far as the margins of the shell material, and from such points of view the shell edges are substantially or entirely concealed. In fact, the edges of the shell material are not noticeable unless the box is viewed substantially in the plane of one of the end wings.

As shown in Fig. 3, after the box is otherwise completed and in some cases while the glue that secures the parts of the blank together is still moist, the edge portions of the end wings may be smoothed down or pressed so that the cover material is more or less rolled over and extended beyond the edges of the shell material, for instance as shown at *m*. This pressing or swaging of the exposed edges may be carried about the three edges of each of the end wings.

There is thus produced a box part which resembles very closely box parts of the most expensive and perfect kind, but which by modified and simplified structure is much cheaper, both because of the saving of material and the simplification of the method of folding and securing in complete box formation.

I claim:

1. A covered paper box comprising a cardboard shell and a paper cover overlying outer surfaces of the shell, corner laps of the shell being inwardly located at the end walls of the box with their inward edges close together, marginal portions of the cover being inturned and secured to margins of the box wall around the entire inner circumference of the box, the shell end wings being adhesively secured to outer surfaces of the corner laps.

2. A covered paper box comprising a cardboard shell and a paper cover overlying outer surfaces of the shell, corner laps of the shell being inwardly located at the end walls of the box with their inward edges close together, marginal portions of the cover being inturned and secured to margins of the box wall around the entire inner circumference of the box, the shell end wings being adhesively secured to outer surfaces of the corner laps, the edges of the shell end wings being more or less exposed.

3. A covered paper box comprising a card-

board shell and a paper cover overlying outer surfaces of the shell, corner laps of the shell being inwardly located at the end walls of the box with their inward edges close together, marginal portions of the cover being inturned and secured to margins of the box wall around the entire inner circumference of the box, the shell end wings being adhesively secured to outer surfaces of the corner laps, edge portions of the cover material overlying the shell end wings being pressed down to partially obscure the shell end wing edges.

4. A covered paper box comprising a cardboard shell and a paper cover overlying the outer surfaces of the shell, corner laps of the shell being inwardly located at the end walls of the box with their inward edges close together, marginal portions of the cover being inturned and secured to margins of the box wall around the entire inner circumference of the box, the shell end wings being adhesively secured to outer surfaces of the corner laps, the end wings and corner laps having substantially the same vertical length.

5. A covered paper box comprising a cardboard shell and a paper cover overlying the outer surfaces of the shell, corner laps of the shell being inwardly located at the end walls of the box with their inward edges close together, marginal portions of the cover being inturned and secured to margins of the box wall around the entire inner circumference of the box, the shell end wings being adhesively secured to outer surfaces of the corner laps, the end wings and corner laps having substantially the same vertical length, the edges of the shell end wings being more or less exposed.

6. A covered paper box comprising a cardboard shell and a paper cover overlying the outer surfaces of the shell, corner laps of shell being inwardly located at the end walls of the box with their inward edges close together, marginal portions of the cover being inturned and secured to margins of the box wall around the entire inner circumference of the box, the shell end wings being adhesively secured to outer surfaces of the corner laps, the end wings and corner laps having substantially the same vertical length, exposed edge portions of the cover material overlying the shell end wings being pressed down to partially obscure the shell end wing edges.

7. A covered paper box consisting of a cardboard shell and cover material substantially covering outer surfaces of the shell, the end walls of the box comprising shell corner laps continuous with side wings of the box and having their inward edges closely adjacent, and shell end wings overlying and adhesively secured to the corner laps and overlaid by a portion of cover material

leaving the edges of the shell end wings more or less exposed, portions of the cover material being turned in and adhesively secured to inner marginal surfaces of the shell throughout the entire interior circumference of the box.

8. A covered paper box composed of a blank assembly comprising a rectangular sheet of shell material having a body, side wings, end wings and corner laps extending from ends of the side wings, the shell being overlaid by a sheet of cover material having two opposite margins turned over and adhesively secured to inward marginal surfaces of the shell along the outer edges of the side wings and corner laps, the assembly being slit to separate the corner laps from the end wings, the blank being folded in box form with the corner laps innermost at the ends of the box so that the inturned cover margins are substantially continuous throughout the interior of the box, giving the appearance of a covered box of more or less conventional form, the end wings overlying and adhesively secured to the corner laps with edge portions of the shell more or less exposed.

9. A covered paper box composed of a blank assembly comprising a rectangular sheet of shell material having a body, side wings, end wings and corner laps extending from ends of the side wings, the shell being overlaid by a sheet of cover material having two opposite margins turned over and adhesively secured to inward marginal surfaces of the shell along the outer edges of the side wings and corner laps, the assembly being slit to separate the corner laps from the end wings, the blank being folded in box form with the corner laps innermost at the ends of the box so that the inturned cover margins are substantially continuous throughout the interior of the box, giving the appearance of a covered box of more or less conventional form, the end wings overlying and adhesively secured to the corner laps with edge portions of the shell more or less exposed, the edges of the cover material adjacent to the exposed edges of the shell end wings being pressed over to partially obscure the exposed edges of the shell.

10. A blank assembly for covered boxes, comprising a rectangular shell having a body portion, side and end wings, and corner laps extending from ends of the side wings, and a sheet of cover material overlying one side of the shell and of substantially the same outline and having side marginal portions turned over and secured to the opposite side of the shell material throughout the length of the side wings and corner laps, the blank being dimensioned so that when folded into box form with the corner laps inwardly turned within the end wings, the overturned marginal portions of the cover are substantially continuous about the inner margins of the box walls.

11. A covered paper box comprising a shell and overlying cover material, an edge of the shell material exteriorly located on one wall of the box having the adjacently-terminating cover material pressed down and partially overlapping and concealing said shell-edge.

12. A covered paper box structure comprising a shell, a cover sheet overlying exterior shell surfaces and having portions folded over and concealing certain edges of the shell, a portion of the cover sheet having an exterior edge terminating in approximate alinement with an exposed edge of an underlying exterior member of the shell, said cover edge being pressed over said exposed shell edge to substantially conceal the latter.

13. A covered paper box-part comprising a shell having a body portion, side wings, in-turned corner-laps, and end wings overlying the corner-laps and having exposed edges at the outside of the box structure, and a cover sheet overlying outer surfaces of the shell, marginal portions of the cover sheet being turned over and concealing edges of the side wings and corner-laps, portions of the cover sheet overlying the shell end wings having edges cut close to said exposed end-wing edges and pressed down over the latter to partially conceal them.

Signed at New York city, in the county of Kings, and State of New York, this 22nd day of April A. D. 1921.

HARRY BRIDGMAN SMITH.
